CONDUCTOR SUPPORT

John J. Taylor, Wadsworth, Ohio, assignor to The
Ohio Brass Company, Mansfield, Ohio, a cor-
poration of New Jersey

Application February 20, 1936, Serial No. 64,859

7 Claims. (Cl. 173—313)

This invention relates to conductor clamps for insulators of the post or pin type, and has for one of its objects the provision of a simple and effective clamp for securing a conductor on top of an insulator and one which will be more effective than the tie wire heretofore used for this purpose.

A further object of the invention is to provide a conductor holder for a pin type insulator which will not produce radio disturbances.

A further object of the invention is to provide a pivoted clamp that can be mounted on the top of an insulator and that will hold the conductor firmly against movement in the direction of its axis but will yield to vertical vibrations of the conductor so as to avoid bending at the clamp.

A further object of the invention is to provide a device of the class named which shall be of improved construction and operation.

Other objects and advantages will appear from the following description.

The invention is exemplified by the combination and arrangement of parts shown in the accompanying drawing and described in the following specification, and it is more particularly pointed out in the appended claims.

In the drawing:

Fig. 1 is an elevation with parts in section showing one embodiment of the present invention.

Fig. 2 is a top plan view, partly in section, of the device shown in Fig. 1.

Fig. 3 is half elevation and half section of the clamp shown in Figs. 1 and 2.

The numeral 10 designates any insulator of the post or pin type having a recess in its upper end in which an insert 11 is secured by cement 12. The insert 11 carries a clamp base 13 having upwardly projecting ears 14 on which are mounted a pair of inwardly extending axially aligned pintles 15, one on each of the ears 14. An elongated conductor seat or cradle 16 is provided with a pair of laterally extending bosses 17, each of which is provided with a downwardly opening pocket 18 for receiving a pintle 15. The upper end of each pocket 18 is closed by a bridge bar 19 which rests on the pintle 15 and supports the cradle 16. It will be seen that because the pockets 18 are open at their lower ends, the cradle 16 may be readily set down over the pintles 15 and will be pivotally supported by engagement between the pintles 15 and their cooperating bearing bridges 19. The conductor seat or cradle 16 will rest in place by gravity and has pivotal movement about the line of contact at the top of the pintle 15. The bearing pocket of the pintle

15 is large enough to permit slight pivotal movement upon the upper element of the pintle 15 without relative sliding of the bearing surfaces. This, as will be seen from Fig. 3, locates the axis of the pivotal movement substantially in horizontal alignment with the longitudinal axis of the cable in the conductor seat. This pivotal movement will not tend to shift the cable in a longitudinal direction and will produce less bearing pressure at the end of the cable seat than would be the case if the axis of pivotal movement were either above or below the longitudinal axis of the cable.

If the axis of the cable were above the pivotal axis of the cradle 16, any longitudinal stress on the cable would produce a moment tending to rotate the cradle upon its axis, due to the lever arm between the axis of the cable and the pivotal axis of the seat. This would cause one end of the seat to press against the cable, forming a node for the cable vibrations, and an initial stress tending to aggravate fatigue at the node produced by the pressure of the end of the cable seat against the cable. Furthermore the moment of the seat pressing one end against the cable would hold the seat locked against free movement upon its pivot, thus neutralizing the benefits of the pivotal mounting, insofar as it relieves the effects of vibration. With the construction shown, however, any unbalanced longitudinal stress on the cable will be exerted directly in line with the pivotal axis of the seat and hence will produce no rotating moment of the seat.

If the pintles were fixed to the cradle and rested in bearings in the supporting ears, the pivotal rotation would be about the lowest element of the pintle rather than the top element, and it would be necessary to raise the pintle an amount equal to its own diameter as compared with the arrangement of Fig. 3, in order to bring the pivotal axis in alignment with the longitudinal axis of the cable. This, of course, would increase the effective length of the insert above its point of embedment in the insulator and thus add to the bending moment of the force exerted by the conductor on the insulator. By connecting the pintles to the support rather than to the cradle, the cantilever action on the insulator is decreased because of this difference in lever arm length.

Although the cable support rests by gravity upon its pintles, it sometimes happens that the contour of the conductor line is such that there is an uplift on the conductor, which would tend to raise the cradle off of its supporting insulator. To avoid any possibility of accidental displacement, the bolts which hold the keeper on the

conductor are made to serve the additional function of locking the cable seat in place. These bolts are designated by the numeral 20 and extend up through the pockets 18 just inside the ends of the pintles 15. The lower ends of the bolt shanks are squared to fit the pockets 18 so as to hold the bolts against rotation and each bolt is provided with a head 21 which engages the cradle 16 at the lower end of the pocket 18.

10 The outer edge of the bolt head 21, as will be seen from Fig. 3, bridges the portion of the pocket into which the pintle 15 projects, thus locking the pintle in the pocket and preventing accidental displacement of the cradle from its bearing. It 15 will also be noted that the outer square face of the bolt shank engages the inner ends of the pivot studs 15 so as to prevent transverse movement of the cradle. Any lateral force on the conductor will be counteracted by pressure on the ends of 20 the pintles 15 which will withstand the force without producing any serious friction to interfere with the pivotal movement of the cradle.

15 The upper ends of the bolts 20 engage a keeper 22 by means of which the cable is clamped in the seat 16. The keeper 22 is provided with two bearing faces 23 and 24 having different radii of curvature and being offset vertically different distances relative to the ends of the keeper. By 25 this arrangement, cables of a large range of diameters may be clamped in the conductor seat. Nuts 26 and lock washers 25 are provided for holding the keeper piece in place.

30 In attaching a conductor to an insulator by means of the device described, the bolt heads 21 are first located beneath the pintles 15 and then the cradle 16 is lowered into place with the bolts projecting through the pocket openings. The conductor is then located in the seat and the clamp 22 placed over the ends of the bolts with 35 the bearing seat, which best fits the particular cable, turned downwardly. The nuts are then tightened up to secure the conductor in place. By this arrangement, a simple means is provided for securing all the advantages of the pivoted clamp 40 for a conductor mounted on a pin type insulator. The insert 11 not only firmly holds the clamping means in place but also acts as an insulated flux control for screening the exposed parts of the fitting and preventing corona from any exposed 45 portion of the fitting. The lower end of the insert 11 is, of course, closer to the ground connection than any other part of the fitting so that the electrostatic flux will tend to emanate from the part of the fitting covered by the insulation 50 rather than from any exposed point; and since the end of the fitting 11 is in direct electrical connection with the surface of the porcelain 10 through the interposed cement, the formation of corona at this point is entirely avoided.

55 The form of pivotal mounting makes it possible to locate the cable very close to the top of the insulator so as to avoid greatly increasing the cantilever action. The pivotal mounting permits vertical movement of the conductor support 60 at the point where the conductor leaves the support so as to avoid fatigue of the conductor strands by bending at this point. At the same time, the clamp provides a permanent grip on the conductor which holds the conductor against 65 slipping relative to the insulator, and thus maintains the proper division of the catenary sag between the various conductor supports.

70 The device is particularly convenient for what is commonly referred to as "hot line" operations, that is, operations with the conductor energized.

The only equipment that is required is an insulated wrench for loosening the nuts 26, since the same nuts serve to clamp the cable and to lock the conductor support to the insulator. By loosening the nuts 26, the clamp is unlocked from 5 the supporting pinions and loosened on the cable so that it may be slid along the cable out of the way without completely separating the parts of the clamp. This will permit replacement of a defective insulator or other desired operation after 10 which the clamp may be slid into position on the newly installed support and the nuts re-tightened. Simply loosening the nuts is very easily effected on a "hot line", but where it is necessary to remove and replace the parts of the clamp, the 15 operation is much more difficult.

I claim:

1. An insulator of the pin or post type having a recess in the top thereof, a metal support having a projection cemented in said recess, a bearing pintle carried by said support, and a conductor clamp having a bearing opening therein and engaging said pintle and resting thereon for pivotally supporting a conductor on said pintle said clamp having pivotal movement about the top 25 element of said pintle and having a transversely curved cable seat, the longitudinal axis of said seat extending transversely to the pivotal axis of said seat on said pintle, the bottom of said seat being spaced below the level of said element a 30 distance approximately equal to the radius of curvature of said seat.

2. In combination, a support having a pair of pivot studs in axial alignment thereon, a cradle for a conductor, said cradle having pockets engaging said studs, a keeper for holding the conductor in said cradle, and means for locking said pivot studs in said pockets having locking means also holding said keeper in engagement with a conductor in said cradle. 40

3. A conductor support comprising a cradle, a pivot stud for supporting said cradle, said cradle having a pocket therein for receiving said stud, a keeper for holding a conductor in said cradle, and a bolt for holding said keeper on said cradle 45 and for locking said pivot stud in said pocket.

4. A conductor support comprising a dielectric member having a recess in the top thereof, a metal fitting mounted on said dielectric member and having a projection thereon cemented in said recess, said fitting having upwardly projecting spaced ears, inwardly extending pivot studs mounted on said ears in axial alignment with each other, a cradle having downwardly opening pockets in the opposite sides thereof for engaging said pivot studs, a keeper for holding a conductor in said cradle, and bolts for holding said keeper on said cradle, the heads of said bolts being disposed across the lower ends of said pockets for locking said pivot studs in said pockets. 55

5. A conductor support comprising a dielectric member, a fitting mounted on said member and having inwardly extending pivot studs, a cradle having pockets in opposite sides thereof for receiving said studs, a keeper for securing a conductor in said cradle, and a pair of bolts for holding said keeper on said cradle, the heads of said bolts being arranged to close said pockets to lock said pivot studs in said pockets, the ends of said studs being arranged to engage said bolts to limit 70 movement of said cradle in the direction of the axis of said studs.

6. A conductor support comprising a pivotal mounting, a clamp pivotally supported on said mounting and common locking means for secur- 75

ing said clamp to a conductor and for locking said clamp on said mounting, said locking means being releasable to permit displacement of said clamp relative to said conductor and to said mounting without completely disassembling said clamp.

7. In combination a clamp for holding a conductor, a pivotal support for said clamp and a common bolt and nut for holding said clamp in

engagement with said conductor and for locking said clamp on said pivotal support, said nut being releasable to permit displacement of said clamp relative to said conductor and to said support without completely removing said nut from said bolt. 5

JOHN J. TAYLOR.
